LEMON SQUEEZER

John B. Guttman, Hoboken, N. J., assignor to
Squeezit Corporation, New York, N. Y., a corporation of New York

Application November 14, 1952, Serial No. 22,285

Term of patent 14 years

(Cl. D44—29)

To all whom it may concern:

Be it known that I, John B. Guttman, a citizen of the United States, residing at Hoboken, county of Hudson, and State of New Jersey, have invented a new, original, and ornamental Design for a Lemon Squeezer, of which the following is a specification, reference being had to the accompanying drawings, which form a part thereof.

In the drawings:

Fig. 1 is a side elevation of a lemon squeezer, showing my new design;
Fig. 2 is a plan view thereof;
Fig. 3 is a front elevation thereof;
Fig. 4 is a rear elevation thereof; and
Fig. 5 is a side elevation of the squeezer as it appears when open.

I claim:

The ornamental design for a lemon squeezer, as shown.

JOHN B. GUTTMAN.
